J. YATES

DRAFT MOTOR

Filed June 6, 1921

UNITED STATES PATENT OFFICE.

JOHN YATES, OF SAN FRANCISCO, CALIFORNIA.

DRAFT MOTOR.

Application filed June 6, 1921. Serial No. 475,223.

To all whom it may concern:

Be it known that I, JOHN YATES, a citizen of the United States, residing at San Francisco, in the county of San Francisco and 5 State of California, have invented new and useful Improvements in Draft Motors, of which the following is a specification.

This invention relates to improvements in flue draft operated power units and resides 10 in the provision of a simple, inexpensive and compact motor which is particularly adapted for use in connection with the flue of a stove, furnace or like apparatus and is constructed so as to operate by force of the 15 draft and products of combustion passing upwardly in the flue.

The primary object of the invention is to provide a motor of the character described which may be made comparatively small 20 and compact and easily installed in connection with a furnace or stove flue so as to take up little space and will provide maximum power at practically no expense, for use in operating roasting spits or other stove or 25 furnace apparatus or other apparatus, such as dynamos and power machinery.

Another object is to provide a motor of the character described which may be put into and out of operation at will without interfering with the furnace or having an undesirable effect on the flue draft.

A further object is to provide a motor of the character described which may be used in connection with apparatus other than 35 stove or furnace flues since it may be operated by any fluid impelling medium and is constructed so as to permit free passage of the fluid regardless of the character of the fluid, thru the motor there being comparatively little obstruction to the flow offered 40 by the motor.

The invention possesses other advantages and features some of which, with the foregoing will be set forth at length in the following description where I shall outline in full that form of the invention which I have selected for illustration in the drawings accompanying and forming a part of the present specification. In said drawings I have 45 shown one form of the construction of my invention, but it is to be understood that I do not limit myself to such form since the invention as expressed in the claims may be embodied in a plurality of forms.

50 Referring to the drawings:

Figure 1 is a front elevation the motor of

this invention, being broken away in part and shown in vertical section.

Figure 2 is a vertical section taken on line 2—2 of Fig. 1. 60

Figure 3 is a top plan view of the motor.

Figure 4 is a side elevation showing the motor installed with a flue and as used for operating a roasting spit, the flue being broken in part and shown in section. 65

Referring to the drawing, 1 designates a frame in the upright sides 2 of which a shaft 3 is journalled at its ends as at 4. A cylindrical casing 5 surrounds the shaft 3 and houses a rotor 6 secured to said shaft. On 70 one end of the shaft outside the casing is a fly wheel 7 whereas a gear wheel 8 is fixed to the other end of the shaft.

As shown in Fig. 4, the gear 8 meshes with a pinion 9 and has a roasting spit 10 75 which latter will extend into a furnace, not shown. I may use the motor for operating other devices as desired, the above use being an example only of its many uses.

The flue 11 of a furnace oven or stove, not shown, is provided with a branch pipe 12 leading outward and upwardly from one side thereof, the one end of the casing 5 and this pipe serves as the draft intake for the casing. A damper or valve 13 is mounted 80 in the pipe 12 near its intake end and a similar damper 14 is mounted in the flue 11 just above the pipe 12. An outlet pipe 15 leads from the other end of the casing 5 and back to the flue 11. The foregoing is exemplary 85 of the manner of incorporating the motor with the flue of a furnace, stove or oven and it will be apparent that other analogous means of supplying a flue impelling medium may be employed if desired. 90

The motor comprises a plurality of separate units or impellers 16, 17, 18, 19 each of which comprises a hollow cylindrical closed drum 20 fixed to the shaft and having four or more flat blades 21 extending radially 100 from its periphery. Each unit is mounted in a separate compartment, there being four compartments designated 22, 23, 24 and 25. These compartments are provided by extending a plurality of spaced partitions 26, 105 transversely across the casing 5, which latter is closed on all sides except where the pipes 12 and 15 are connected thereto. The blades 21 extend so that the ends and sides thereof are close to the sides and outer walls 110 of the compartments.

A conduit 27 is formed so as to extend

helically around the casing from the intake pipe 11 to the outlet pipe 15. This conduit communicates with each compartment for a distance equal to about one fourth of the circumference of each impeller drum, said compartments being open as shown at 28 and 29 in Fig. 2. The conduit opens into the compartment 22 for the impeller 16 near the upper side of the compartment and is straight as shown at 30, where this communicates, so that one of the blades 21 extends into and practically will close the conduit at this point and will be subjected to the full force of the impelling medium passing thru the conduit. The conduit then curves as at 31, so as to extend around the outer wall 32 of the casing to the next compartment 23 where at a point opposite the portion 30 is communicated with the chamber 23 thru the opening 29. The conduit is straight as at 33 at this point so that the blades 21 will close or better, extend fully into the conduit thru the opening 29. The conduit then passes around in another arcuate portion 34 around the cylindrical casing wall 32, and on to the conduit 24 where at the next quarter point extends into said chamber in the same manner as shown in Fig. 2 and finally likewise communicates with the final chamber 25 and from thence continues to the outlet pipe 15.

When the flue damper 14 is closed and the damper 13 opened the draft and products of combustion will shunt off thru the pipe 11 and into the helical conduit 27. This impelling fluid will impinge against the blades 21 of the impeller 16, pass on into the compartment 23 and operate against the blades 21 of the impeller 17 and so on into the compartment 22.

ments 24 and 25 impinging against the blades 21 of the impellers 18 and 19 then finally passing out thru the pipe 15 back to the flue. When the first impeller 16 has made one revolution the fluid will have acted upon each of the four impellers. This results in the provision of a steady and effective power which taken out thru the gear wheel, may be transmitted to the spit or any other mechanism or machine as desired.

The special motor arrangement provides for maximum power development, with minimum resistance to the flow of the draft or impelling fluid thru the motor and in this way soot, cinders, etc., will not be subject to damaging or clogging the motor.

I claim:

1. The combination with an outlet flue, of a casing remote from the flue, an intake pipe leading off from the flue to the casing, an outlet pipe leading from the casing back to a point in the flue above the casing, a rotor in the casing, and a helical conduit extending around and communicating at spaced points between its ends with the exterior of the casing and at its ends with the intake and outlet pipes respectively.

2. The combination with an outlet flue, of a casing remote from the flue, an intake pipe leading off from the flue to the casing, an outlet pipe leading upwardly from the casing back to the flue, a rotor in the casing, and a helical conduit extending around and communicating at spaced points between its ends with the exterior of the casing and at its ends with the intake and outlet pipes respectively, a damper in the flue above the intake pipe, and a damper in the intake pipe.

JOHN YATES.
